UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

TRUCK FOR RAILWAY-CARRIAGES.

SPECIFICATION forming part of Letters Patent No. 408,022, dated July 30, 1889.

Application filed January 3, 1889. Serial No. 295,322. (No model.)

To all whom it may concern:

Be it known that I, EDWARD WILLIAM MACKENZIE HUGHES, of Chicago, Cook county, Illinois, have invented a new and useful Truck 5 for Railway-Carriages, of which the following is a full, true, and exact description, reference being had to the accompanying drawings.

My invention relates to an improved truck for railway-carriages, in which the parts are 10 mostly made of pressed steel. The structure of this truck will be readily understood from the accompanying drawings, the novelty of which is pointed out in the claims hereto annexed.

15 Figure 1 represents a plan view of my truck with some of the parts removed; Fig. 2, a lateral view of the said truck-frame, showing the position of the bolster-beam and bolster-beam box; Fig. 3, an inside view, partly in 20 section, showing the same structure from the opposite side; Fig. 4, a plan view, partly broken away, showing the bolster-beam and spring-supports; Fig. 5, a vertical section through the same on the line $x-x$; Fig. 6, an 25 elevation of the bolster-beam; Fig. 7, a plan view of the same; Fig. 8, a view of the same looked at from beneath; Fig. 9, a section through the center of the same; Fig. 10, a view of the lower journal attached to the 30 bolster-beam; Fig. 11, a view of the bottom of the upper journal attached to the car-body, and Fig. 12 a view of the upper surface of the part shown in Fig. 11.

A represents the side frames of the truck, 35 which are made of pressed steel and flanged, as shown in detail in Fig. 2. The end pieces or boxes B serve to unite the side frames together. The side frames A are provided with openings C for the axle-boxes, and with a 40 flanged opening D for the passage of the bolster-beam box. The bolster-beam box is shown in section, Figs. 2 and 3, and is made of pressed steel for the reception of the hollow bolster-beam itself, which is likewise made 45 of pressed steel. The flaring sides E of the bolster-beam box are cut away at the ends, as shown, so as to allow the bolster-beam box to pass through the opening D and to be riveted to the flanged side openings, as shown in Figs. 50 2 and 5. Within the bolster-beam box is

placed the pressed steel bolster-beam M, (itself shown in detail in Figs. 6, 7, 8, and 9,) which is itself a box of pressed steel of the shape shown. To the center of this is fastened the bolster-journal F, Fig. 10, also of 55 pressed steel, within which the part G moves when the car is in operation. The springs are placed between the bolster-beam and the bolster-beam box, as clearly shown in Fig. 5, and they rest upon pressed-steel plates H at 60 their upper and lower ends, which plates are provided with projections K, fitting within the ends of the springs, which plates may rest upon wooden blocks, as shown.

The truck-frames A are made of flanged 65 pressed steel, and the ends of the bolster-beam box pass through the openings in the truck-frames, the flaring flange being cut away at the ends, so as to permit the ends of this bolster-beam box to be passed through 70 and be riveted to the flange, as plainly shown in Figs. 2 and 5.

The end frames B are preferably made of pressed steel, and preferably bolted to the 75 ends of the side frames by bolting through the side flanged frames and through these pressed-steel box-beams, as shown.

I do not in this application, however, claim this specific method of attachment or the relation of the side plates and end plates of the 80 truck, having filed another application therefor simultaneously herewith, Serial No. 295,324. Nor do I in this application claim as separate articles the pressed-steel wearing-journals described, having filed another application therefor simultaneously herewith, 85 Serial No. 295,321. Nor do I in this application claim the bolster-beam and bolster-beam box of pressed steel, having filed another application therefor simultaneously herewith, 90 Serial No. 295,323.

What I claim as my invention, and desire to secure by Letters Patent, is—

1. The combination, in a railway-truck, of the pressed-steel truck-frames provided with 95 a flanged opening for the reception of a bolster-beam box, a pressed-steel bolster-beam box fitting the flange of said opening and extending transversely from truck-frame to truck-frame and having its exterior ends sup- 100

ported by the flanges of said truck-frames and fastened thereto, and a pressed-steel bolster-beam vertically movable in said box, substantially as described.

5. 2. The combination of the pressed-steel box, bolster-beam M, the pressed-steel bolster-beam box E, the spring-plates H H, and the springs inclosed in said pressed-steel box, and the truck-frames A, provided with flanges D, integral therewith and forming supports for the bolster-beam box E, which is attached to said flanges, substantially as described.

3. The combination of the pressed-steel truck-frames A A, the pressed-steel cross-

pieces B B, having closed box ends surrounding and fitting the ends of the truck-frames A, the pressed-steel bolster-beam box E, the the pressed-steel bolster-beam M, and the pressed-steel journal-plates F G, substantially as described.

In testimony whereof I have signed my name to this specification in the presence of two subscribing witnesses.

EDWARD WILLIAM MACKENZIE HUGHES.
